F. BAYERDOERFER.
DRYING FRAME FOR LACE CURTAINS.

No. 593,387

Patented Nov. 9, 1897.

Fig. 1.

Fig. 2.

UNITED STATES PATENT OFFICE.

FRANK BAYERDOERFER, OF BROOKLYN, NEW YORK.

DRYING-FRAME FOR LACE CURTAINS.

SPECIFICATION forming part of Letters Patent No. 593,387, dated November 9, 1897.

Application filed April 1, 1897. Serial No. 630,235. (No model.)

To all whom it may concern:

Be it known that I, FRANK BAYERDOERFER, a citizen of the United States, residing at Brooklyn, in the county of Kings and State of New York, have invented certain new and useful Improvements in Drying-Frames for Lace Curtains, of which the following is a specification.

This invention relates to certain improvements in drying-frames for lace curtains by which any number and size of curtains can be stretched and dried with great facility, the stretching-frame being readily folded up after use into a small compass, so as to be stored away until again required; and the invention consists of a stretching and drying frame for lace curtains which comprises inclined tubes connected by V-shaped holders having a center sleeve and set-screw for clamping the top rod of the frame and rods applied to the ends of the curtains and locked to the inclined side tubes by means of adjustable clamps, said end rods having adjustable collars, so as to adjust the distance of the inclined main tubes any length from each other. The inclined main tubes and lower stretching-rods are provided with pins that engage the edge of the curtains and stretch the same tightly in position in connection with the top, as will be fully described hereinafter and finally pointed out in the claims.

In the accompanying drawings, Figure 1 represents a perspective view of my improved frame for stretching and drying curtains. Fig. 2 is a perspective view, partly in section, of a portion of the stretching-frame, showing the connecting parts on a larger scale; and Figs. 3 and 4 are detail side views of the stretching-pins for the lace curtains.

Similar letters of reference indicate corresponding parts.

Referring to the drawings, A A represent inclined main tubes which are held at an angle to each other by the V-shaped pieces B, which are provided with pins b, that extend for a certain distance in the upper portion of the inclined main tubes A. The V-shaped piece B is provided with a central sleeve b', that is arranged at right angles to the plane of the same and that serves for supporting the top rod C of the stretcher-frame. The said top rod is firmly clamped to the V-shaped pieces

B by a set-screw b², that passes through the apex of the V-shaped piece and which binds on the top rod C, as shown in Figs. 1 and 2. 55 Longitudinal stretcher-rods D are arranged along the lower part of the inclined main tubes A and are provided with adjustable collars d, having a set-screw d' to retain them at the proper distance between the inclined 60 main tubes A. The lace curtains are stretched over the top rod and connected to the lower rods D by means of shiftable stretching-hooks E, which are applied by eyes e to the lower rods D, said hooks being of any approved 65 shape, but which are preferably formed with an angular shank that is made integral with the eye, said shank having a sharp pointed end, so as to pass readily through the edge of the curtains, as shown in Fig. 1. After the 70 ends of the curtains are attached by the angular pins to the lower rods D the side edges of the curtains are connected to the inclined main tubes A by similar pins F, which are provided with eyes f, by which they slide 75 along the main tubes A, so as to be arranged at proper distance from each other. The stretching of the lace curtains is produced by retaining the lower rods D on the main tubes A by means of T-pieces G, which are provided 80 with sleeves g and set-screws g', the upper ends of the T-pieces serving to support the lower stretching-rods D before the curtains are stretched, while the lower part of the T-pieces G serve to retain the rods D after the 85 curtain is stretched, the T-pieces being firmly attached to the main tubes by the set-screws g', so as to retain them firmly in position. Any number of lace curtains may be stretched over the stretching-frame, that is formed of 90 the main tubes A A, top rod C, lower rods D, and thus dried in a very convenient manner without requiring the large and unhandy wooden stretching-frames having stationary stretching-pins on all the sides of the stretch- 95 ing-frame.

When my improved stretching-frame is to be used, the main tubes A A are first connected to the pins b of the V-shaped pieces B. The top rod C is then placed through the 100 sleeves b' of the V-shaped pieces B and clamped in position by the set-screw b². The lower stretching-rods D are then placed in position on the upper part of the T-shaped pieces

- G. The curtains are then placed over the top rod and applied to the shiftable stretching-pins of the lower stretching-rods, after which the shiftable stretching-pins on the 5 main tubes are applied to the side edges of the curtains and stretched tightly by the same. The lower stretching-rods are then finally placed in position against the lower part of the T-pieces G and the latter moved along 10 the main tubes, if required, so as to apply the proper degree of tension to the curtains, in which position the curtains are permitted to dry. After they are thoroughly dried the pieces G are loosened, the curtains first 15 moved from the lower stretching-rods, then from the stretching-pins of the main tubes A, and finally removed from the stretching-frame, which is then placed in a narrow compass by removing the main tubes from the V-shaped connecting-pieces and the top rod from the sleeves of the same, so that the main tubes 20 and rods can be stored in a comparatively small bundle until they are again required for use.
- 25 My improved stretching-frame for drying lace curtains is preferably made of steel tubes, iron or brass rods, while the V-shaped connecting-pieces and the T-pieces are preferably made of suitable cast metal, being either 30 finished by japanning or nickel-plating, according to the finish that is desired to be given to the stretching and drying frame.
- My improved stretching and drying frame for lace curtains forms a convenient and durable device for domestic use and can be more 35 conveniently stored than the unhandy wooden stretching-frames in use for this purpose.
- Having thus described my invention, I claim as new and desire to secure by Letters 40 Patent—
1. In a stretching and drying frame for lace curtains, the combination of main tubes, V-shaped connecting-pieces for said main tubes,

a top rod connecting said V-shaped pieces, stretching-rods, adjustable T-pieces applied 45 to the main tubes for retaining the lower stretching-rods, and shiftable stretching-pins applied to the inclined main tubes and lower stretching-rods so as to engage the edges of the sides and ends of the curtains as they are 50 stretched over the top rods, substantially as set forth.

2. In a stretching and drying frame for lace curtains, the combination of inclined main tubes with a V-shaped connecting-piece having pins extending into the upper ends of said main tubes, a sleeve arranged in the upper part of said V-shaped connecting-piece, a top stretching-rod passing through said sleeve, and a set-screw for holding the top rod in position in the sleeve, substantially as set forth. 55

3. In a stretching and drying frame for lace curtains, the combination of inclined main tubes, of adjustable T-pieces provided with sleeves and set-screws, and a lower stretching-rod adapted to be retained in position by 60 said T-piece being applied either above or below the shank of the same, substantially as set forth. 65

4. In a stretching and drying frame for lace 70 curtains, the combination of inclined main tubes, of adjustable T-pieces having sleeves and set-screws, of a lower stretching-rod provided with a collar and set-screw for adjustment to said T-piece, said stretching-rod being either supported on the shank of said T-piece or below the shank of the same, substantially as set forth. 75

In testimony that I claim the foregoing as my invention I have signed my name in presence of two subscribing witnesses.

FRANK BAYERDOERFER.
